Primary Examiner — Elizabeth J Oswecki(74) *Attorney, Agent, or Firm* — QuickPatents; Kevin Prince(57) **CLAIM**

I claim the ornamental design for a LED illumination tile, as shown and described.

DESCRIPTION

FIG. 1 is a top perspective view of a LED illumination tile, showing my new design;

FIG. 2 is a bottom perspective view thereof;

FIG. 3 is a top perspective view thereof, shown in a used condition;

FIG. 4 is a top plan view thereof;

FIG. 5 is a bottom plan view thereof;

FIG. 6 is a rear elevational view thereof;

FIG. 7 is a front elevational view thereof;

FIG. 8 is a left-side elevational view thereof; and,

FIG. 9 is a right-side elevational view thereof.

The broken lines shown in the drawings represent portions of the LED illumination tile that form no part of the claimed design.
